UNITED STATES PATENT OFFICE.

FREDERICK P. UHRIG, OF ALTOONA, WASHINGTON.

EXHAUST TANK.

Application filed February 5, 1924. Serial No. 690,885.

This invention relates to an apparatus for subjecting canned material to the action of steam, the general object of the invention being to provide means for causing the cans 5 to pass in a spiral path in a steam receptacle.

Another object of the invention is to provide means whereby the cans can be introduced into the device in a steady stream and to provide means for ejecting the cans from 10 the apparatus.

This invention also consists in certain other features of construction and in the combination and arrangement of the several parts, to be hereinafter fully described, illustrated in the accompanying drawings and 15 specifically pointed out in the appended claims.

In describing my invention in detail, reference will be had to the accompanying 20 drawings wherein like characters denote like or corresponding parts throughout the several views, and in which:—

Figure 1 is a side view of one form of the invention.

Figure 2 is a plan view with parts broken away.

Figure 3 is a section on line 3—3 of Figure 2.

Figure 4 is a section on line 4—4 of Figure 1.

Figure 5 is a section on line 5—5 of Figure 1.

Figure 6 is a view of the spring 19.

Figure 7 is a view of the recessed member 16.

Figure 8 is a view of the seat carrying member 14.

Figure 9 is a plan view, partly in section, showing a modification.

40 In these views 1 and 2 indicate a pair of tanks which are supported upon the uprights 3. Each tank is provided with a spirally arranged flange 3' upon its inner wall which forms a spiral path for the cans.

45 The drum 4 is rotatably mounted in each tank and this drum is formed with semi-circular recesses 5 in its circumference for receiving portions of the cans, the other portions of the cans lying in the space formed by the spiral flange so that as the drum is rotated the cans will be forced up the path formed by the flange. The drums are arranged on shafts 6 which extend through the bottoms of the tanks and which are connected by the gears 7 to a horizontally arranged shaft 8. The gear on shaft 6 of one

of the tanks is connected by a gear 9 with a shaft 10 which is provided with a pulley 11 so that the drums can be rotated from any suitable source of power. A casing 12 is connected with one side of the tank 1 and is in communication with the inlet opening of this tank. A carrier 13 is arranged in the casing 12 and said carrier consists of a lower member 14 which carries the can seats 15 and an upper member 16 which is provided with semi-circular recesses 17 in its circumference for receiving portions of the cans seated upon the seats 15. The seats 15 project into the tank 1 and are engaged by the recesses in the drum in this tank so that the carrier is rotated by the movement of the drum. It is mounted upon the shaft 18 journaled in the casing. An opening 20 places the casing 12 in communication with the tank 1 so that cans can pass from the casing into the tank where they will be pushed off the seats 15 and upon the flange 3' by the drum during the rotation of the parts and a spring 19 is provided for directing the cans upon the seats of the carrier at the inlet opening 22 of the casing 12. The cans are fed through the inlet opening by the conveyor means 23 which may be of any ordinary construction and they are taken from the discharge 24 of the tank 2 by a conveyor 25. A carrier 26 and its casing 27 is arranged between the upper parts of the tanks 1 and 2 for conveying the cans from tank 1 into tank 2. This carrier is similar to the carrier before described. The tanks 1 and 2 are provided with detachable tops 28 which have openings therein which communicate with openings in the casing 27 for permitting the carrier 26 to receive the cans from the tank 1 and deliver them to the tank 2. The tanks are provided with the steam pipes 29 and the drain pipes 30 so that the cans passing through the tanks are subjected to the action of steam.

40 In the modification a single tank 1' is shown and the cans reaching the upper end of the spiral path in this tank are directed through the discharge spout 31 by means of the flange 32 which is carried by the top 28' of the tank. In this latter case the cans only pass through the one tank but in the first case the cans pass upwardly through one tank and are then carried to the other tank by the carrier 26 and in this tank they pass downwardly to the discharge 24. As will be seen the cans are automatically passed

through the steam tanks and by making the tanks of different sizes or using different numbers of tanks the canned material can be subjected to the action of steam for any desired period of time.

I prefer to form the drums as shown in the drawings though they may be formed in any other way. As shown in these drawings the drums consist of a series of rings 10 33 fastened to the shaft 6 by the spokes 34 and having semi-circular recesses in their circumferences with vertical bars 34' connecting the recessed edges of the rings together, these bars forming a plurality of 15 vertically arranged grooves in the drum through which the cans pass as the drum is being rotated and the cans being forced through the grooves by the spiral flange in the tank.

20 It is thought from the foregoing description that the advantages and novel features of my invention will be readily apparent.

I desire it to be understood that I may make changes in the construction and in the

combination and arrangement of the several parts, provided that such changes fall within the scope of the appended claim.

What I claim is:—

An apparatus of the class described comprising a tank having a spiral flange on its inner wall, a drum having semi-circular recesses in its circumference for holding cans on the flange, means for rotating the drum and a member for delivering cans to the tank, said member comprising a lower disk 30 and an upper disk connected together, the lower disk having spaced semi-circular enlargements on its periphery forming can seats and the upper disk having recesses 35 therein for receiving portions of the cans resting upon the seats, the seat forming portions entering the recesses in the drum as the drum rotates so that the movement of the drum will be communicated to the feeding member. 40

45 In testimony whereof I affix my signature.

FREDERICK P. UHRIG.
